Fig. 11.

Fig. 12

FIG. 1 is a perspective view of a diagnostic multiple test viewing rack for test tubes;

FIG. 2 is a front elevation of FIG. 1 at a reduced scale;

FIG. 3 is a plan view of FIG. 2;

FIG. 4 is a rear view of FIG. 2;

FIG. 5 is a left elevation of FIG. 2 enlarged;

FIG. 6 is a vertical cross section taken along lines 6—6 of FIG. 1 at an enlarged scale;

FIG. 7 is a perspective view of the top portion of the diagnostic multiple test viewing rack for test tubes of FIG. 1;

FIG. 8 is a front elevation of FIG. 7;

FIG. 9 is a plan view of FIG. 8;

FIG. 10 is a rear elevation of FIG. 8;

FIG. 11 is a left elevation of FIG. 8 on an enlarged scale;

FIG. 12 is a vertical cross sectional view enlarged, taken along lines 12—12 of FIG. 10;

FIG. 13 is a perspective view of the base portion of the diagnostic multiple test viewing rack for test tubes of FIG. 1;

FIG. 14 is a plan view of FIG. 13;

FIG. 15 is a side elevation of FIG. 14; and

FIG. 16 is an end elevation of FIG. 14.

I claim:

A diagnostic multiple test viewing rack for test tubes, substantially as shown.
